MULTIPLE RECORD SUPPORT FOR
PHONOGRAPHS

Harold Walker, Meadowbrook, Pa., assignor, by
mesne assignments, to Philco Corporation,
Philadelphia, Pa., a corporation of Pennsyl-
vania

Application December 28, 1943, Serial No. 515,959

11 Claims. (Cl. 274—10)

1

This invention relates to phonographs, more particularly to an improved multiple record player or record changer for phonographs of the automatic type. The invention, moreover, is especially concerned with a record supporting mechanism which may be loaded with a plurality of records to be played, the mechanism being arranged to successively deliver the records to the turntable in an automatic manner.

Many different types of record changers have already been used and proposed for use, but at least most of them are subject to a number of disadvantages and difficulties of types mentioned below.

In one common prior type of mechanism, a stack of records was supported above the turntable, centered on the turntable spindle, the records of the stack being supported directly one upon another. In many arrangements of this type the records are successively released for descent to the turntable by a pair of "knife" devices arranged toward opposite sides of the turntable, the knife blades being rotatable about vertical axes and so arranged that one pair of knives moves between the two lowermost records of the stack when the lowest one is being dropped to the turntable. In this way the remainder of the stack remains supported above the turntable, while the "dropped" record is being played. Disadvantages of this type of mechanism arise from the fact that the records are not all of uniform thickness and, moreover, are quite frequently warped, as a result of which the knife blades frequently chip the edges of the records and even break records, for instance, in cases where a particularly badly warped record is encountered.

In accordance with another common type of multiple record support sometimes called the "push-off" type, a stack of records is threaded upon a turntable spindle. The mechanism for successively dropping the records to the turntable, in at least certain arrangements, operates in such a manner that the record is pushed against the spindle with a substantial force, thereby tending to enlarge the center hole of the record. Moreover, in this type, the records frequently commence their descent to the turntable in an inclined position, which also tends to promote wearing of the center hole of the record. As is well understood, enlargement of the center hole is a serious disadvantage because of the inaccurate reproduction which occurs from a record which is not running "true."

Some of the primary objects of the invention are concerned with overcoming difficulties and

2

disadvantages of the types mentioned above, and to do this by means of a mechanism which is effective and reliable in operation and which is composed of readily fabricated parts.

According to the invention, provision is made for individually supporting a plurality of records above the turntable by means of a plurality of independent record supporting shelves or plates which are spaced from each other a distance sufficient to accommodate records of different thickness as well as records which may be more or less warped.

The invention provides for the individual and independent support of each record in horizontal position coaxially of the turntable axis and spindle, the record release being effected in a manner to drop each record in a truly horizontal position and thereby avoid wear of the center hole.

According to another feature of the invention, provision is made for quick and convenient loading from a position directly above the turntable, and without the necessity for displacing actuating arms or other parts of the mechanism.

With the foregoing general statement of objects and advantages in mind, attention is now directed to the following description of a preferred embodiment, during which description additional objects and advantages will appear as the more or less specific details of the mechanism are understood.

In the accompanying drawings—

Figure 1 is a plan view of a phonograph incorporating the mechanism of the present invention, with certain parts removed for the sake of illustration;

Figure 2 is an elevational view of various parts of the mechanism, the view being taken in the direction indicated by the line 2—2 on Figure 1;

Figure 3 is a vertical sectional view through a record supporting mechanism constructed according to the invention, this view being on a substantially enlarged scale as compared with Figures 1 and 2 and being taken generally in a radial plane containing the axis of the turntable;

Figure 4 is a fragmentary view similar to Figure 3 but illustrating a different position of certain parts; and

Figure 5 is a horizontal sectional view taken as indicated by the line 5—5 on Figure 3, the view, however, being on a somewhat reduced scale.

As seen in Figures 1 and 2, various of the phonograph parts are mounted on a base 6. The turntable is shown at 7 and its spindle at 8. At diametrically opposite positions a pair of record supporting posts 9—9' are arranged, each of

these posts serving to carry a plurality of record supporting shelves as will further appear. The tone arm is shown at 10, the tone arm being pivoted as at 11 on the base and carrying a suitable pick-up 12, adapted to cooperate with records on the turntable. For automatic cyclic operation, the motions of the tone arm may be controlled by a cycling cam, the outline of which appears at 13 in Figure 1, the same being shown in elevation in Figure 2. It will be understood that an appropriate drive is provided for the turntable and also that switches or other controls such as shown in outline at 14 are ordinarily provided but the details of these parts, and also of features such as the cycling cam and its action in moving the tone arm, need not be considered herein, since such features form no part of the present invention per se. The cycling cam and its operating mechanism, and the arrangement for moving the tone arm by rotation of the cam, may be of the general character disclosed in the Cranmer et al. application, Serial No. 407,788, filed August 21, 1941, now Patent No. 2,339,981 granted January 25, 1944.

The record supporting posts 9 and 9' are similar in construction and operation, and in Fig. 1 the elements of post 9' have been designated by primed numerals. In the subsequent description, reference is made to post 9 for convenience and simplicity. Each of the record supporting posts 9 comprises a pair of uprights 15 (Figure 2) which are connected at their lower ends by means of a plate 16, and at the top by a cross-tie 17. Each post unit is mounted on the base 6 by means of a pair of guides 18 providing for guided movement of the post toward and away from the turntable, this arrangement being provided in order to accommodate records of different sizes. Each post may be retained in adjusted position by means of a locking device 19.

Between the uprights 15 of each post a plurality of plates 20 are arranged, the plates being spaced from each other and superimposed in a series to receive rearwardly projecting tongues 21a formed as parts of the record supporting shelves 21. As best seen in Figure 5, the plan pattern of the record supporting shelves is such as to cooperate with the record over an appreciable arc thereof adjacent the periphery. Records R are shown supported by certain of the upper shelves 21 in both Figures 2 and 3. From examination of Figure 3 in particular it will be seen that each of the record supporting shelves is arranged between a pair of the mounting plates 20 with freedom for sliding movement toward and away from the axis of the turntable. The upper shelves in Figure 3 are in record supporting or advanced position, whereas the lower shelves in Figure 3 are in non-supporting or retracted position. It will further be observed that the mounting of the shelves 21 provides freedom for limited angular oscillation of the shelves, for which purpose upper and lower projections defining pivot points are provided on the shelves, as indicated at 22 and 23, respectively (see also Figure 5).

Attention is now called to the fact that the rearward projections 21a of the shelves 21 are provided adjacent their rear corners with tabs 24 which serve as stop members adapted to engage behind complementary stops 25 (see Figures 3 and 5), the several stop members 25 being arranged in a series spaced from each other. Such stop members may conveniently be formed by notching a pair of strips 26, which strips are

mounted on the post as is clearly seen in Figures 2 and 3.

Turning again to the movement of the record supporting shelves between advanced and retracted positions, it is now pointed out that springs 27, one for each shelf, arranged alternately at opposite sides of the post, serve to urge the shelves to advanced position. In advanced position, the tabs 24 at the rear edge of the shelf enter the notches 28 which intervene between the series of stops 25. On the other hand when a shelf is in retracted position, for instance the second shelf from the bottom in Figure 3, the tabs 24 engage behind the cooperating stops 25, this position being maintained by virtue of the forward and downward inclination of the associated spring 27.

During the various motions of the record supporting shelves, especially the angular oscillatory movement thereof, the pivot projections 22 and 23 cooperate with the fixed mounting plates 20, above and below, in maintaining appropriate spacing between the shelves and also in facilitating free shelf movement.

According to the invention, mechanism is provided for controlling the action of the shelves, this mechanism including a sliding bar 29 arranged to pass through apertures formed in both the fixed mounting plates 20 and in the record supporting shelves 21, such apertures being indicated at 30 and 31, respectively, in Figures 3 and 4. The apertures in the plates 20 serve as a guide for the bar 29 and, as will plainly be seen from the mid-portion of Figure 3, the apertures 35 in the record supporting shelves are so located as to be in part out of registry with those in the fixed plates 20 when the record supporting shelves are in advanced position. Note now that the upper end of the bar 29 has an inclined face 32 arranged to cooperate with rear edges of the apertures 31 in the record supporting shelves and thereby retract the shelves as the bar 29 is moved upwardly.

During this upward movement of the bar 29, as the shelves are retracted, the springs 27 act to oscillate the shelves into positions in which the stop-tabs 24 engage behind stops 25. This action proceeds in step-by-step fashion under the control of mechanism described herebelow. The step-by-step movement of bar 29 results in successive dropping of the records R onto the turntable. It may here be noted that the turntable spindle is desirably of height sufficient to engage in the center holes of all of the records carried by the posts 9, in order that the records will be properly guided in their descent to the table.

When the bar 29 reaches the upper limit of its stroke, i. e., when all of the records have been dropped to the turntable, the bar may be withdrawn downwardly, which action will not cause the record supporting shelves to move outwardly to advanced position because of the inter-engagement of the stop-tabs 24 with the stops 25. However, upon reaching the lowermost position, the lowermost record supporting shelf 21 will be free to move inwardly to record supporting position because of the fact that no stops 25 are provided for this one shelf of the series. The reason for this will be clear from the discussion of Figure 4 just below:

Figure 4 shows the bar 29 in lowermost position, the full line showing of the bottom shelf 21 indicating that this shelf is in advanced position, which is in contrast with all of the others 75 which are at that time held retracted. In this

condition, the posts are ready to be loaded with a group of records to be played. To accomplish loading the group of records may be held above the turntable in position to descend on the turntable spindle. The first record is then released and descends to rest upon the lowermost shelves 21 of the two posts. As is shown in Figure 4 the weight of this first record R1 causes the lowermost shelf 21 to oscillate somewhat to the position indicated at 21b, in which the rear end of the projection 21a is raised. This brings abutments 33 (see also Figure 5) into engagement with the underside of the next higher shelf, thereby oscillating the next higher shelf to the position indicated at 21c in which it is disengaged from the stops 25. The spring 27 associated with this plate may now move this shelf to advanced position, as indicated at 21d. The second shelf is thus "tripped" by the placing of a record on the first. In turn, the third is similarly tripped by the placing of a record on the second, and so forth through the series.

An extremely simple, rapid and effective loading system is thus provided. It is also of convenience that the loading may be accomplished from above the turntable and without the swinging back or displacement of any control arms or other parts of the mechanism.

After completion of the loading, the control bar 29 is moved upwardly as above described in order to successively drop the records on the turntable. The controlled upward movement of bar 29, according to the invention, is advantageously brought about by mechanism under the general control of the usual cycling cam with which automatic phonographs are provided, such a cam being shown at 13 in Figure 2. For the above purpose a lower extension 29a of the bar 29 is provided with ratchet teeth 34 with which a toothed ratchet member 35 cooperates. The member 35 is pivoted as at 36 to a link 37 which in turn is pivotally carried at 38 on a fixed bracket 39. The link 37 may be raised by an arm 40 fixed to a shaft 41 (see also Figure 1), the arm 40 being coupled with link 37 by another pivoted link 42. Shaft 41 has another arm 43 fixed thereto, which is extended adjacent to the cycling cam 13 and carries a cam follower 44 adapted to ride on the cam itself and to be actuated by the cam projection 45. With these parts arranged as just described, downward swinging of arm 43, when actuated by cam projection 45, causes the linkage 42-42 to lift ratchet 35, thereby raising the bar 29.

As is known in this art, cycling cams such as shown at 13 in Figure 2 are arranged to be actuated in timed relation to the playing of the records. The invention contemplates that the arm 43 shall be actuated at a time just following withdrawal of the tone arm and this actuation of arm 43 raises the ratchet 35 and thereby lifts the control bar 29 to release another record for descent to the turntable. The bar 29 is retained in its new position by means of a toothed catch 46, adapted to cooperate with the ratchet teeth 34, the catch 46 being formed as a part of the pivoted arm 47, which arm is biased to its upper position by means of a tension spring 48. Each time the ratchet 35 is raised, the catch 46 will be displaced and snap into the next lower ratchet notch of control bar extension 29a.

When the control bar has been moved step-by-step to its uppermost position, it may be released for return movement (downwardly) by a

control linkage such as shown at 49, which, upon downward movement, for instance manually, will disengage not only the holding pawl 47 but also the stepping pawl 35, whereupon the return spring 50 will draw the control bar downwardly to condition the record supporting posts for re-loading. Prior to re-loading, however, the previously played group of records should be lifted from the turntable, since, upon downward movement of the control bar the lowermost pair of record supporting shelves will again be moved to advanced position and would thus interfere with removal of records from the turntable.

It should be observed that various of the actuating and control parts are duplicated for each of the record supporting posts, although a single transverse operating shaft 41 (see Figure 1) serves to couple both posts with the cycling cam 13.

As mentioned above, each of the posts, including the actuating bar 29, is adjustable sufficiently to permit the use of different sized records, e. g. ten and twelve inch records. Accordingly the post is mounted in an elongated opening as shown at 51 in the upper right-hand corner of Fig. 1. In this illustration the uprights and shelves of the record support structure are removed to show the adjustable mounting more clearly.

Since pawl members 35 and 46 are supported by the bracket 39 which is fixedly secured to the base plate 6, the said members are so formed as to permit adjustment of the posts while still maintaining engagement between the pawl members and the ratchet teeth. The stepping pawls and associated elements are shown in dotted outline in Fig. 1 (see particularly the right-hand post structure). The pawl 35 is of extended length and has integral arms 52 and 53 secured by pivot pin 36 to links 37 which in turn are pivotally secured to depending arms 54 of bracket 39. Arm 53 is further extended and is connected to the release member 49 through a pin and slot connection, as shown in Fig. 2.

The holding pawl and associated elements are shown in dotted outline in Fig. 5. This pawl is also of extended length and has integral arms 55 pivotally secured to the arms 54 of the bracket 39. The pawl also has an arm 56 which is connected to the release member 49 through a pin and slot connection as shown in Fig. 2.

From the foregoing description it will be seen that a multiple record support has been provided of a type having a number of advantages as compared with various arrangements of the prior art. The action of the record supporting shelves which are carried by the posts is such as to have no tendency to damage the records during operation, either by chipping or scratching. Moreover, the records are individually carried by pairs of independent supporting shelves, rather than being stacked one directly upon another, which is also of importance in avoiding damage to the records. The arrangement of the record supporting shelves and the action thereof is also such as to drop each record in a truly horizontal position, without any tendency to cant the record, and without any tendency to push the record against the turntable spindle. Wear of the center holes of the records is thereby avoided.

In addition to the foregoing it may be mentioned that the several parts of which the posts are composed are of types which are very readily fabricated and assembled. The mechanism is also unusually reliable in operation and not easily subject to damage or misadjustment, in view of

which servicing and repair are reduced to a minimum.

I claim:

1. In a phonograph having a turntable, mechanism for supporting a record above the turntable and for releasing the record for descent to the turntable comprising a record supporting shelf and mounting means for the shelf including a substantially horizontal guideway providing for guided horizontal movement of the shelf between a record supporting or advanced position and a non-supporting or retracted position, the shelf further being mounted with freedom for limited angular oscillation when in retracted position, and stop means adapted to be engaged by the shelf upon oscillation thereof in one direction and serving to prevent horizontal movement of the shelf to its advanced position.

2. A construction in accordance with claim 1 and further including yielding means for urging the shelf toward its advanced position upon oscillation of the shelf in the direction disengaging the stop means.

3. In a phonograph having a turntable, mechanism for supporting a record above the turntable and for releasing the record for descent to the turntable comprising a record supporting shelf and mounting means for the shelf including a substantially horizontal guideway providing for guided horizontal movement of the shelf between a record supporting or advanced position and a non-supporting or retracted position, yielding means for urging the shelf toward its advanced position, the shelf further being mounted with freedom for limited angular oscillation, stop means adapted to be engaged by the shelf upon oscillation of the shelf in one direction when the shelf is in retracted position, which stop means thereupon serve to prevent horizontal movement of the shelf to its advanced position, and means for oscillating the shelf to disengage it from the stop means and thereby provide for movement of the shelf to its advanced position under the influence of said yielding means.

4. A construction in accordance with claim 3, incorporating a plurality of shelves as defined in claim 3, the shelves being arranged in superimposed relation to give support to a plurality of superimposed records, and means automatically operative upon the placing of a record upon one shelf to disengage the next higher shelf from its cooperating stop means, whereby in loading the shelves with a plurality of records, the placement of a record on one shelf conditions the next higher shelf to receive the following record.

5. In an automatic phonograph, a turntable, a plurality of similar record-supporting structures adapted to support a group of records above the turntable, said structures furnishing the only support for the records, each of said supporting structures including a plurality of superimposed record supports each adapted to engage one of the records, each of said supports being movable from a supporting position to a non-supporting position, spring means urging each support to its supporting position, and means for moving the corresponding supports of said supporting structures to their non-supporting positions in upward progression to cause successive dropping of the supported records onto the turntable.

6. In an automatic phonograph, a turntable, a plurality of record-supporting structures adapted to support a group of records above the turntable, each of said supporting structures including a plurality of superimposed relatively spaced record-

supporting shelves each adapted to engage one of the records, whereby the records are individually supported in superimposed spaced relation, each record being supported by corresponding shelves of said supporting structures, each of said shelves being movable between supporting and non-supporting positions, means urging each shelf to its supporting position, means for moving the corresponding shelves of said supporting structures to their non-supporting positions in upward progression to cause successive dropping of the supported records onto the turntable, means for latching each shelf in its non-supporting position, excepting the lowermost shelf of each supporting structure, and means whereby the corresponding shelves of said supporting structures are released in upward progression during reloading.

7. In an automatic phonograph, a turntable, a plurality of record-supporting structures adapted to support a group of records above the turntable, each of said supporting structures including a plurality of superimposed relatively spaced record-supporting shelves each adapted to engage one of the records, whereby the records are individually supported in superimposed spaced relation, each record being supported by corresponding shelves of said supporting structures, each of said shelves being movable between supporting and non-supporting positions, means urging each shelf to its supporting position, means for moving the corresponding shelves of said supporting structures to their non-supporting positions in upward progression to cause successive dropping of the supported records onto the turntable, means for latching each shelf in its non-supporting position, excepting the lowermost shelf of each supporting structure, and means whereby the corresponding shelves of said supporting structures are released in upward progression during reloading.

8. In an automatic phonograph, a turntable, a plurality of record-supporting structures adapted to support a group of records above the turntable, each of said supporting structures including a plurality of superimposed relatively spaced record-supporting shelves each adapted to engage one of the records, whereby the records are individually supported in superimposed spaced relation, each record being supported by corresponding shelves of said supporting structures, each of said shelves being movable between supporting and non-supporting positions, means urging each shelf to its supporting position, means for moving the corresponding shelves of said supporting structures to their non-supporting positions in upward progression to cause successive dropping of the supported records onto the turntable, means for latching each shelf in its non-supporting position, excepting the lowermost shelf of each supporting structure, and means on each shelf operative when a record is placed thereon to release the next higher shelf, whereby the corresponding shelves of said supporting structures are released in upward progression during reloading.

9. A multiple record supporting and releasing mechanism for a phonograph, comprising a plurality of spaced superimposed mounting plates, a

plurality of apertured record-supporting shelves mounted respectively between consecutive pairs of the plates with freedom for sliding movement between a record supporting or advanced position and non-supporting or retracted position, and an actuating member movable step-by-step into the apertures of the shelves and having an inclined face adapted to cooperate with the shelf apertures to successively retract the shelves according to the step-by-step movement of the actuating member.

10. A multiple record supporting and releasing mechanism for a phonograph, comprising a plurality of spaced superimposed mounting plates, a plurality of apertured record-supporting shelves mounted respectively between consecutive pairs of the plates with freedom for sliding movement between a record supporting or advanced position and a non-supporting or retracted position, yielding means adapted to urge the shelves toward advanced position, and an actuating member movable step-by-step into the apertures of the shelves and having an inclined face adapted to cooperate with the shelf apertures to successively retract the shelves according to the step-by-step movement of the actuating member.

11. In a phonograph having a turntable, a record supporting post carrying a plurality of superimposed record supports arranged to give support to a plurality of records above the turntable, the post being movable toward and away from the turntable to accommodate records of different sizes, and control means for actuating the record supports including operating means

5

10

15

incorporating a connection accommodating the movement of the post toward and away from the turntable, in which the operating means for the record supports includes notched and toothed members having cooperating surfaces paralleling the path of movement of the post, one of said members being movable with respect to the other upon movement of the post, and one of said members having its cooperating surface extended sufficiently to insure engagement with the other member in different positions of the post.

HAROLD WALKER.
